ADJUSTABLE TRIGGER STOP

Jack J. Staller, Winthrop, Mass.

Application January 7, 1946, Serial No. 639,681

6 Claims. (Cl. 89—27)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a machine gun and particularly to a novel and improved stop for the trigger bar generally provided in such guns.

In the U. S. Army models of the Browning machine guns, for example, the caliber .50, M2, machine gun, a trigger bar member is provided comprising a relatively long member pivotally mounted at its central portion to the receiver and constructed to provide an operative connection between the sear on the bolt of such machine gun and a back plate trigger. Elevating the rear end of such trigger bar has the effect of depressing the forward end toward the bolt in position to trip off the sear as the bolt approaches its battery position.

Considerable difficulty has heretofore been experienced in correctly positioning such trigger bar with respect to the bolt and the sear. A fixed stud is generally provided, depending from the top plate of the machine gun, and such stud is arranged to limit the upward movement of the rear end of the trigger bar. When all of the cooperating components are produced to exact dimensions, then the fixed trigger bar stop should limit the movement of the rear end of the trigger bar so that the front end clears the top of the bolt by a few thousandths of an inch. In quantity production of machine gun components, however, it is not possible to produce dimensionally identical components. Accordingly, even under the best manufacturing conditions, an accumulation of tolerances in the cooperating members quite often produces assemblies with one of two extreme conditions existing. For example, the trigger bar stop may be too short relative to the various cooperating elements so that the front end of the trigger bar actually interferes with and rides upon the top surface of the bolt. This condition, while undesirable from the standpoint of wear of the components, is dangerous in that it has the effect of tripping the sear slightly earlier than usual and hence there is a possibility of firing the cartridge before the action is safely locked. Or in the other extreme combination of tolerances, the trigger bar stop is relatively long compared to the other components and the forward end of the trigger bar is stopped a substantial distance above the top of the bolt. If this separation is extreme, it is possible for the trigger bar to miss the sear entirely and hence be inoperative to fire the gun.

Accordingly, it is an object of this invention to provide an improved trigger bar stop for a machine gun. A particular object of this invention is to interchangeably provide an adjustable trigger bar stop for a Browning machine gun, 60

2

such, for example, as the U. S. machine gun, caliber .50, M2.

The specific nature of the invention as well as other objects and advantages thereof will clearly appear from a description of a preferred embodiment as shown in the accompanying drawings in which:

Fig. 1 is a side elevational view, partly in section, of a machine gun incorporating a trigger bar stop in accordance with this invention.

Fig. 2 is an isometric view of the assembly of components constituting one modification of a trigger bar stop in accordance with this invention.

Fig. 3 comprises top and front elevational views of an assembly of components constituting a second modification of this invention.

Fig. 4 comprises a side and a partial angular elevational view of the spring utilized in the construction of Fig. 3.

In any modification of a military weapon to incorporate improvements, the primary criterion is that such modification be completely interchangeable with existing weapons and be capable of being applied to the gun in the field. In accordance with this invention, an adjustable trigger bar stop is provided for Browning-type U. S. Army machine guns which is interchangeable with existing guns and may be applied without the use of special tools and equipment.

In Fig. 1 there is shown a machine gun receiver 1 having side plates 2 and 3 and top plate 4. A bolt 5 is arranged in conventional fashion to reciprocate within receiver 1 and on the upper surface of bolt 5, a conventional sear 6 is provided to trip the firing mechanism (not shown). An integral lug 7 is provided in depending relationship on top plate 4 and a trigger bar 8 is pivotally mounted within receiver 1 by means of a pin 9 passing through suitable holes in trigger bar 8 and lug 7. A conventional trigger bar stop 10 may be provided comprising a depending stud-like member mounted in top plate 4 immediately overlying the rear end 11 of trigger bar 8. It should be understood, however, that it is immaterial to the practice of this invention whether or not the standard fixed trigger bar stop 10 remains in the weapon.

The adjustable trigger stop unit comprises a rectangular base member 20 (Fig. 2) on which is provided a hollow stud 30 which in turn is externally threaded to receive an adjustable nut 40. Base member 20 is secured in depending relationship to top plate 4 by means of a special screw 21 which is substituted for the standard rear top plate cover screw. The hollow stud 30 may be formed integrally with base member 20 as shown or may be secured in a suitable hole in the base member 20. In any event, a cylindrical opening 22 is provided extending through

both base member 20 and stud member 30 which is large enough to receive the standard fixed trigger bar stop therein. The end of such standard trigger bar stop, if retained in the gun, is, however, shortened by cutting or filing off approximately one-tenth of an inch. Adjusting nut 40 is screwed on to the external threads provided on stud 30. Adjusting nut 40 is constructed to lie in the path of trigger bar 8 and serves as a stop therefor and rotation of nut 40 on stud 30 serves to adjust the vertical position of the nut with respect to the trigger bar stop.

In the modification disclosed in Figs. 1 and 2, rotation of the adjusting nut 40 after it has been set to proper position is prevented by the inter-engagement of the trigger bar 8 between depending integral prongs 41 provided on adjusting nut 40.

In the modification illustrated in Figs. 1 and 2, three such prongs are provided and hence adjustments can be made at intervals of $\frac{1}{3}$ of a turn of adjusting nut 40, but obviously any number of prongs may be utilized as desired.

A further modification of this invention is disclosed in Figs. 3 and 4. As illustrated in these figures, a U shaped, leaf-type latching spring 50 is provided having one arm 51 somewhat longer than the other arm 52. A hole 53 is provided in arm 51 of suitable dimensions to accommodate hollow stud 30. An arcuate recess 54 is provided in arm 52 in alignment with hole 53. An adjusting nut 60 is provided which is screwed onto hollow stud 30 after latching spring 50 is assembled thereon.

There is provided a base member 24 similar to member 20 but having a cut-out portion 23. Arm 51 of latching spring 50 is bent to form a projecting portion 55 which in assembly fits snugly in cut-out portion 23 and thereby secures spring 50 against rotation.

An integral detent 56 is formed in arm 52 of spring 50 in such manner as to engage in serrations 61 provided on the top surface of adjusting nut 60.

The latching spring 50 thus serves to resiliently secure nut 60 against rotation. Nut 60 can thus be readily adjusted to and maintained in a proper position to function as a stop for trigger bar 8.

It will be apparent that the modification shown in Fig. 3 has the further advantage of permitting adjustment of the trigger bar stop merely by removal of the back plate (not shown) of the gun. It is not necessary to disassemble the trigger bar as is the case with the construction of Fig. 2.

I claim:

1. For use in a machine gun having a movable trigger bar, a trigger bar stop comprising a threaded stud arranged to be secured to the gun and disposed in the path of the trigger bar, a nut member mounted on said stud and arranged to be engaged by the trigger bar to limit the movement thereof, and a plurality of axially extending projections provided about the periphery of said nut member, said projections being spaced apart relative to each other so as to receive the trigger bar therebetween in any one of a plurality of rotative positions of said nut member of said stud.

2. For use in a machine gun having a movable trigger bar, a trigger bar stop comprising a threaded stud arranged to be secured to the gun and disposed in the path of the trigger bar, a nut member mounted on said stud and arranged to

be engaged by the trigger bar to limit the movement thereof, a leaf spring mounted in surrounding relation on said stud between said nut member and the machine gun, means for non-rotatively securing one end of said leaf spring to the machine gun, and a detent formed on said leaf spring, said nut member having a plurality of circumferentially spaced notches arranged to selectively receive said detent.

3. For use in a machine gun having a trigger bar pivotally movable in a vertical plane, a trigger bar stop comprising a plate-like base member arranged to be secured to the machine gun in a position overlying the trigger bar, a threaded stud formed on said base member and projecting into the path of the trigger bar, a nut member mounted on said stud and adapted to be engaged by the trigger bar to limit the movement thereof, a generally U-shaped latch spring having both arms mounted on said stud between said nut member and said base member, said base member having a recess constructed and arranged to receive one arm of said latch spring therein to non-rotatively secure said latch spring to said base member, and a detent formed on the other arm of said latch spring, said nut member having a plurality of circumferentially spaced notches arranged to selectively receive said detent therein, thereby resiliently securing said nut member in any selected one of a plurality of rotative positions on said stud.

4. In a machine gun having a trigger bar pivotally movable in a vertical plane, a fixed stud-like trigger bar stop cooperating with said trigger bar to limit the movement thereof, the improvement comprising, a hollow threaded stud member arranged to surround the fixed trigger bar stop, means for securing said stud member to the machine gun in surrounding relation to the fixed trigger bar stop, a nut member mounted on said stud member and arranged to be engaged by the trigger bar to limit the movement thereof, and means for securing said nut member in any selected rotative position on said stud member.

5. The combination defined in claim 4 wherein said last mentioned means comprises a plurality of axially extending projections provided about the periphery of said nut member, said projections being spaced apart relative to each other so as to receive the trigger bar therebetween in any selected one of a plurality of rotative positions of said nut member on said stud member.

6. The combination defined in claim 4 wherein said last mentioned means comprises a leaf spring mounted in surrounding relation on said stud member between said nut member and the machine gun, means for non-rotatively securing one end of said leaf spring to the machine gun, and a detent formed on said leaf spring, said nut member having a plurality of circumferentially spaced notches arranged to selectively receive said detent therein.
